UNITED STATES PATENT OFFICE.

ROWLAND RHODES, OF NEW YORK, N. Y., ASSIGNOR TO WILLIAM H. DURGIRE, OF CONCORD, NEW HAMPSHIRE.

DESIGN FOR A HANDLE FOR SPOONS, &c.

SPECIFICATION forming part of Design No. 22,779, dated September 12, 1893.

Application filed July 8, 1893. Serial No. 479,957. Term of patent 7 years.

To all whom it may concern:

Be it known that I, ROWLAND RHODES, a citizen of the United States, residing at New York, in the county of New York and State of New York, have invented and produced a new and original Design for Handles for Flat and Table Ware; and I do hereby declare the following to be a full, clear, and exact description of the same, reference being had to the accompanying drawings, forming a part thereof.

This invention relates to an original design for flat and table ware and consists in the shape and ornamental configuration which is shown in the accompanying drawings, where-

in—

Figure 1 represents the obverse and Fig. 2 the reverse sides of the handle.

The obverse face of the handle has a beaded border located slightly within the margin terminating at a point near the top and extending to the base or bowl. At the upper end is the fanciful configuration shown which consists of a series or cluster of scrolls extending partway down the edges and at points over the beaded border onto the blank central portion. On the reverse side of the handle the beaded border extends up to the top and terminates in the fanciful design shown.

At intervals over the border are clusters of scrolls of fanciful design. The edge of the handle has a slight swell or bulge at a point a short distance below the top, and the space between the border is blank.

The essential features of the design are the obverse and reverse having the beaded borders terminating near the tops, the fanciful scrolls at intervals extending over the border and the fanciful scroll work at the tops.

What is claimed as new, and desired to be secured by Letters Patent, is—

1. The design for a handle for spoons or similar articles substantially as herein shown and described.

2. In a design for a handle, for spoons or similar articles the obverse, substantially as shown and described.

3. In a design for a handle for spoons or similar articles the reverse, substantially as shown and described.

In testimony whereof I affix my signature in presence of two witnesses.

ROWLAND RHODES.

Witnesses:

H. H. HAMILTON,
HENRY C. MINOT.

It is hereby certified that the name of the assignee in Design Letters Patent No. 22,779, granted September 12, 1893, upon the application of Rowland Rhodes, of New York, N. Y., for a Design for a "Handle for Spoons, &c.," was erroneously written and printed "William H. Durgire," whereas said name should have been written and printed *William B. Durgin*; and that the Letters Patent should be read with this correction therein that the same may conform to the record of the case in the Patent Office.

Signed, countersigned, and sealed this 19th day of September, A. D. 1893.

[SEAL.]

JNO. M. REYNOLDS,
Assistant Secretary of the Interior.

Countersigned:

S. T. FISHER,
Acting Commissioner of Patents.
